UNITED STATES PATENT OFFICE.

JOSEPH R. PALMENBERG, OF NEW YORK, N. Y.

SHOW-STAND.

SPECIFICATION forming part of Letters Patent No. 358,475, dated March 1, 1887.

Application filed January 4, 1887. Serial No. 223,351. (No model.)

To all whom it may concern:

Be it known that I, JOSEPH R. PALMENBERG, a citizen of the United States, residing at New York, in the county and State of New York, have invented a new and Improved Show-Stand, of which the following is a specification.

This invention relates to a stand for displaying dry-goods, and so constructed that the standard or support is located, not in the rear of the stand, as heretofore generally constructed, but in the center thereof. In this way the weight is evenly distributed in the front and rear of the standard.

The invention consists in the various features of improvement hereinafter more fully pointed out.

In the accompanying drawings, Figure 1 represents a perspective view of my improved show-stand. Fig. 2 is a detailed vertical section through one of the caps *e'*.

The letter *a* represents a standard projecting upwardly from foot *b*. The standard *a* is surrounded by three (more or less) sockets, *c*, made in the form of a cross—that is, composed of a pair of tubes crossing at right angles. These sockets may be clamped in place by set-screws *d*.

Into the lateral arms of sockets *c* there enter rods *e*, as shown, and these rods are surrounded at their ends by caps *e'*, clamped in place by set-screws *g*. Each of the caps *e'* is provided at its upper end with two parallel lugs, *e''*, placed at right angles to such cap, as shown.

Between every pair of lugs *e''* there is in-

troduced a rack, *f*, which is held in place by a pin, and which projects an equal distance to the front and rear of rod *e* and extends at right angles to such rod, as shown. The racks *f* may be set at any desired inclination by 40 loosening screws *g* and turning caps *e'*.

Into the teeth of the racks *f* there are placed the parallel bars *h*, one in front and one in the rear of upright *a*, and adapted to support the goods to be displayed.

It will be seen that by this construction one half of the supporting-surface is placed in the front and the other half is placed in the rear of standard *a*, and thus the proper equilibrium is maintained.

If the racks *f* are inclined, the bars *h* may be shifted to maintain the equilibrium.

What I claim is—

1. The combination of standard *a* and foot *b* with the cross-shaped sockets *c*, surrounding standard *a* and having clamp-screws *d*, and with the rods *e*, entering sockets *c* and projecting laterally from standard *a*, and with the racks *f*, supported by rods *e* and projecting to the front and rear of such rods, substantially 55 as specified.

2. The combination of standard *a*, foot *b*, socket *c*, and rods *e*, with the caps *e'*, having lugs *e''* and screws *g*, and with the racks *f*, secured to such lugs and carrying bars *h*, substantially as specified.

J. R. PALMENBERG.
